UNITED STATES PATENT OFFICE.

JENS MOLVIG, OF BUXTON, NORTH DAKOTA.

PROTECTIVE SHIELD FOR SMALL FIREARMS.

1,301,293.

Specification of Letters Patent. Patented Apr. 22, 1919.

Application filed May 19, 1917. Serial No. 169,635.

To all whom it may concern:

Be it known that I, JENS MOLVIG, a citizen of the United States, residing at Buxton, in the county of Traill and State of North Dakota, have invented certain useful Improvements in Protective Shields for Small Firearms, of which the following is a specification, reference being had therein to the accompanying drawing.

10 This invention relates to protective shields for small firearms.

This invention aims to provide in the first instance a shield which is easily removable from and readily affixed to a fire arm and 15 which does not necessitate the annexation of auxiliary fixtures to the firearm, in order to adapt it for receiving and supporting the shield. A coördinate object of the invention is to provide means in connection with 20 a shield for sustaining the impact of projectiles laterally of the longitudinal axis of the firearm.

A further object of the invention is to so construct the fixtures of the shield that they 25 may be collapsed to permit packing of a number of shields together in a small parcel to facilitate transportation.

A still further object of the invention is to removably mount the firearm engaging 30 members upon the shield to permit adjustment thereof to various sizes and types of firearms.

With these and other objects in view the present invention consists in the combination 35 and arrangement of parts hereinafter more fully described, illustrated in the accompanying drawing and particularly pointed out in the appended claim, it being understood that changes may be made in the form, 40 proportion, size and minor details without departing from the spirit of the invention.

In the accompanying drawing:

Figure 1 shows a side elevation of the shield affixed to a firearm.

45 Fig. 2 is a perspective view of the shield detached but engaging a rifle band by way of illustration.

Fig. 3 is a modification.

Referring now more particularly, to the 50 accompanying drawings like characters of

reference indicate like or similar parts throughout the several views.

A common type of firearm has the usual barrel 1, stock 2 and fore-stock 3 upon which is mounted the band 4 provided with 55 a screw threaded opening 4'.

The shield 5 has an opening 6 through which the barrel 1 and fore-stock 3 extend, the opening 6 being sufficiently large to permit sighting of the firearm therethrough. 60 A pair of movable brackets 7 for engaging the fore-stock 3 have opposed outstanding arms 8 carrying thumb screws 9 and are adjustably mounted upon the shield 5 by means of thumb screws 10 extending through trans- 65 verse slots 11. Upon positioning the shield 5 upon the firearm the brackets are moved until the arms 8 thereof abut opposite sides of the forestock 3 and are so held by tightening thumb screws 10 whereupon the thumb 70 screws 9 are turned to bind the shield in position.

Mounted on the shield on opposite sides of the opening 6 are a pair of opposed socket attachments 12 within which are held ball 75 portions 13 of the lateral supports 14 to form a substantially universal connection between the supports and the shield 5. The free terminal ends of the support 14 are slightly bent to form feet and have mounted 80 thereon thumb screws 15 for engagement within the openings 4' in the band 4 to hold the shield in place and sustain lateral impact of projectiles thereupon.

In the modification, the band 4 is provided 85 with thumb screws 15' about which the arms 16' of the bifurcated terminals 17' of the supports extend and are held.

When it is desired to pack the shields the supports 14 are folded inwardly thereupon 90 to make a small and compact parcel readily transported from place to place.

What is claimed is:

The combination with a firearm, of a rectangular shield formed with an opening 95 through which there passes the barrel and fore-stock of a firearm, the opening being of sufficient size to permit sighting of the firearm therethrough, brackets adjustably secured on the rear of the shield and on 100

either side of the opening, means for attaching the brackets to the fore-stock, a band mounted upon the fore-stock, ball sockets mounted on the rear of the shield above and 5 to either side of the opening, supporting members each having one end connected with a ball socket, and means for attaching the remaining ends of the supports to the

said band, whereby the shield is removably secured to the firearm with respect to which 10 it may be given different angles of inclination to ricochet shots for the protection of the user of the firearm.

In testimony whereof I affix my signature.

JENS MOLVIG.
